COMBINED DESK ACCESSORIES AND CALENDAR HOLDER

Jack Bergman, Pittsburgh, Pa., assignor to Pennwood
Numechron Company, Pittsburgh, Pa., a corporation of Pennsylvania

Application November 25, 1958, Serial No. 53,520

Term of patent 14 years

(Cl. D74—5)

Fig.1.

Fig.2.

Fig.3.

Fig.4.

Fig. 1 is a top plan view of a combined desk accessories and calendar holder showing my new design;

Fig. 2 is a front elevation thereof;

Fig. 3 is a vertical section in the plane of line III-III of Fig. 2; and

Fig. 4 is a perspective view thereof.

The back of the article is plain and unornamented, and the left side is the same as the right side.

I claim:

The ornamental design for a combined desk accessories and calendar holder, as shown and described.
